UNITED STATES PATENT OFFICE.

JAMES H. CANNON, OF LOS ANGELES, CALIFORNIA.

TELEPHONE DIRECTORY.

Application filed October 29, 1920. Serial No. 420,444.

To all whom it may concern:

Be it known that I, JAMES H. CANNON, a citizen of the United States, residing at Los Angeles, in the county of Los Angeles and 5 State of California, have invented a new and useful Telephone Directory, of which the following is a specification.

The principal object of my invention is to provide a telephone directory which may 10 be attached to a telephone and by which the telephone user may maintain a convenient list of the numbers most often used by him.

A further object of the invention is to provide such a directory which can be operated 15 by the finger of one hand to find the address of any one listed thereon.

Further objects and advantages will be made evident hereinafter.

Referring to the drawing which is for 20 illustrative purposes only.

Fig. 1 is a perspective view of a telephone equipped with my invention.

Fig. 2 is a side elevation of the directory in its normal or closed position.

25 Fig. 3 is a view of the same in its open position.

Fig. 4 is a plan view of the closed position and Fig. 5 is a plan view of the open position.

30 The directory as shown may be attached to a standard telephone 11 by means of a bracket 12 and a support 13. A flat plate 14 is attached to the support 13 and a platen 15 is pivoted on a pin 16 carried on the 35 plate 14.

It will be noted that the pin 16 is intermediate between the top end 17 and the bottom end 18 of the platen 15, the words top and bottom referring to the position of the 40 parts when viewed as shown in Fig. 4 and 5.

Stacked upon the platen 15 is a stack 45 of cards 20. These cards are all connected together at their upper ends by cloth or other flexible hinges 21, the bottom card being connected to a clip 22 attached to the platen 15. The top edge of the top card is secured to the outer end of the plate 14 by flexible member 25. The bottom edges 50 of cards 20 are cut away as shown in Fig. 4 having index designations 26 thereon. A flat spring 27 attached to the support 13 holds the platen 15 in its upper position as shown in Fig. 2. When held in its upper 55 position, the lower end of each card is exposed and the index markings 26 thereon are exposed.

If the user desires to find a telephone number belonging to, for example, a man named Smith, he presses his finger 30 on the card marked S-T, pressing downwardly thereon. This pushes the bottom end 18 of the platen into the position shown in Fig. 3 against the action of the spring 27, the card marked S-T and all the cards below it in the stack being held flat on the platen by the pressure of the finger. At the same time the top end of the platen 15 is thrown upwardly, pulling the cards above the card marked S-T into a vertical position as shown at 31 in Fig. 3 thus exposing the entire S-T card which contains the Smith number as shown at 33 in Fig. 5. Upon releasing the finger, the parts assume the position shown in Fig. 2, the upper portion of the stack being forced back into position by the downward movement of the top end 17.

I claim as my invention:

1. In combination, a stack of cards so stacked as to expose a portion of the bottom edge of each; means for flexibly connecting the top edges of all said cards together; means for so mounting said stack that the bottom edges of a lower portion of said stack can be forced downwardly by the pressure of a finger; and means by which said downward movement forces the bottom edges of the upper portion of the stack upwardly to expose the top card of said lower portion of said stack.

2. In combination, a support; a platen hinged intermediate to its ends to said support; a stack of cards resting on said platen with a portion of the bottom edge of each card exposed; means for flexibly connecting the top edges of all of said cards together and to said platen; said cards projecting over the top edge of said platen; means for holding the lower edge of said platen in a raised position; and means by which the depression of said platen elevates any cards not held against said platen by external means such as a finger of a user.

3. A telephone directory or the like comprising a support; a platen hinged to said support; a stack of cards resting on said support with a portion of the bottom edge of each card projecting beyond the card above it and the top edges of all cards projecting above the top edge of said platen; flexible means connecting all of said cards together; means for holding the bottom

edge of said platen in a raised position; and elastic means for exerting a downward pull on the top of the top card as the bottom of said platen is depressed.

5 4. A telephone directory or the like comprising a support; a platen hinged to said support; a stack of cards resting on said support with a portion of the bottom edge of each card projecting beyond the card

10 above it and the top edges of all cards projecting above the top edge of said platen; flexible means connecting all of said cards together; means for holding the bottom edge of said platen in a raised position, a

15 member secured to said support and projecting to a point below the top edge of said cards; and means connecting the top edge of said member with the top edge of the top card.

20 5. A telephone directory or the like comprising a support; a platen hinged to said support; a stack of cards resting on said support with a portion of the bottom edge of each card projecting beyond the card

25 above it and the top edges of all cards projecting above the top edge of said platen; flexible means connecting all of said cards together; means for holding the bottom edge of said platen in a raised position, a

30 flat spring member secured to said support and projecting to a point below the top edge of said cards; and means connecting the top edge of said member with the top edge of the top card.

35 6. A telephone directory or the like comprising a support; a platen hinged to said support; a stack of cards resting on said support with a portion of the bottom edge of each card projecting beyond the card

40 above it and the top edges of all cards projecting above the top edge of said platen; flexible means connecting all of said cards together; means for holding the bottom edge of said platen in a raised position, a

45 member secured to said support and projecting to a point below the top edge of said cards; and flexible means connecting the top edge of said member with the top edge of the top card.

50 7. A telephone directory or the like comprising a support; a platen hinged to said support; a stack of cards resting on said support with a portion of the bottom edge of each card projecting beyond the card

55 above it and the top edges of all cards projecting above the top edge of said platen; flexible means connecting all of said cards together; means for holding the bottom edge of said platen in a raised position, a

60 flat spring member secured to said support and projecting to a point below the top edge of said cards; and flexible means connecting the top edge of said member with the top edge of the top card.

65 8. A telephone directory or the like com-

prising a support; a platen hinged to said support; a stack of cards resting on said support with a portion of the bottom edge of each card projecting beyond the card above it and the top edges of all cards projecting above the top edge of said platen; flexible means connecting all of said cards together, a spring secured to said support and pressing upwardly on the bottom edge of said platen for holding the bottom edge of said platen in a raised position; and elastic means for exerting a downward pull on the top of the top card as the bottom of said platen is depressed.

70 9. A telephone directory or the like comprising a support; a platen hinged to said support; a stack of cards resting on said support with a portion of the bottom edge of each card projecting beyond the card

75 above it and the top edges of all cards projecting above the top edge of said platen; flexible means connecting all of said cards together; a flat spring secured to said support and pressing upwardly on the bottom edge of said platen for holding the bottom edge of said platen in a raised position,

80 a member secured to said support and projecting to a point below the top edge of said cards; and means connecting the top edge of said member with the top edge of the top card.

85 10. A telephone directory or the like comprising a support; a platen hinged to said support; a stack of cards resting on said support with a portion of the bottom edge of each card projecting beyond the card

90 above it and the top edges of all cards projecting above the top edges of said platen; flexible means connecting all of said cards together; a spring secured to said support and pressing upwardly on the bottom edge of said platen for holding the bottom edge of said platen in a raised position,

95 a flat spring member secured to said support and projecting to a point below the top edge of said cards; and means connecting the top edge of said member with the top edge of the top card.

100 11. A telephone directory or the like comprising a support; a platen hinged to said support; a stack of cards resting on said support with a portion of the bottom edge of each card projecting beyond the card

105 above it and the top edges of all cards projecting above the top edge of said platen; flexible means connecting all of said cards together; a flat spring member secured to said support and projecting to a point below the top edge of said cards; and means connecting the top edge of said member with the top edge of the top card.

110 12. A telephone directory or the like comprising a support; a platen hinged to said support; a stack of cards resting on said support with a portion of the bottom edge of each card projecting beyond the card

115 above it and the top edges of all cards projecting above the top edge of said platen; flexible means connecting all of said cards together; a spring secured to said support and pressing upwardly on the bottom edge of said platen for holding the bottom edge of said platen in a raised position,

120 a member secured to said support and projecting to a point below the top edge of said cards; and flexible means connecting the top edge of said member with the top edge of the top card.

125 13. A telephone directory or the like comprising a support; a platen hinged to said support; a stack of cards resting on said support with a portion of the bottom edge of each card projecting beyond the card

12. A telephone directory or the like comprising a support; a platen hinged to said support; a stack of cards resting on said support with a portion of the bottom edge 5 of each card projecting beyond the card above it and the top edges of all cards projecting above the top edge of said platen; flexible means connecting all of said cards together; a spring secured to said support 10 and pressing upwardly on the bottom edge of said platen for holding the bottom edge of said platen in a raised position, a flat spring member secured to said support and projecting to a point below the top edge of 15 said cards; and flexible means connecting the top edge of said member with the top edge of the top card.

13. A telephone directory or the like com-

prising a support; a platen hinged to said support; a stack of cards resting on said support with a portion of the bottom edge 20 of each card projecting beyond the card above it and the top edges of all cards projecting above the top edge of said platen; flexible means connecting all of said cards 25 together; a spring secured to said support and pressing upwardly on the bottom edge of said platen for holding the bottom edge of said platen in a raised position; and elastic means for exerting a downward pull 30 on the top of the top card as the bottom of said platen is depressed.

In testimony whereof, I have hereunto set my hand at Los Angeles, California, this 22nd day of October, 1920.

JAMES H. CANNON.
